LOCOMOTIVE FIRE BOX CONSTRUCTION

Charles T. McElvaney, Dallas, Tex.

Application September 6, 1932, Serial No. 631,864

5 Claims. (Cl. 158—3)

This invention relates to a fire box construction for oil burning locomotive engines, boilers, and the like.

Hereinafter for convenience the type of mechanism to which the invention relates will be referred to simply as a locomotive engine, but this is to be understood as illustrative only and not as in any way a limitation upon the scope of the invention.

In locomotive engines of the type under consideration in the arrangement of fire box construction it is the prevailing practice to employ and make an expensive installation of a fire pan, brick work and refractory lining for the fire pan. The fuel ejectors and mixers and the arrangement of burners are also cumbersome and inefficient and it has been found almost impossible to prevent the use of an excessive amount of oil. With the means described in present use a correct functioning of the engine is impaired and an excessive amount of oil is consumed.

The object of this invention is to provide a fire box construction for locomotive engines which will eliminate the costly fire pan, brick work and all refractory lining which is in general use at the present time.

This invention also provides a novel fuel ejector and mixer which is exceptionally efficient and of simple and durable construction which will reduce the amount of oil consumed and add to the efficiency of the engine.

A further object of the invention is the provision of a novel arrangement of the burner by means of which the fire is spread to all parts of the fire box instead of to one certain point as results from the burner and the instrumentalities in use at the present time.

A further object of the invention is to reduce the amount of draft required to lift the fire making it possible to use a larger nozzle tip which eliminates back pressure on the locomotive when it is working.

A still further object of the invention is to place the burner or burner head approximately in the center of the fire box, eliminating certain air openings which are now generally used for admitting air for combustion.

With these and other objects in view the invention consists in general of the structural characteristics and combination of parts illustrated in the accompanying two sheets of drawings, described in the following specification, and particularly pointed out in the appended claims.

In the drawings, wherein like characters of reference indicate like parts in the several views,

Figure 1 is a longitudinal section of a typical locomotive fire box with the construction and arrangement of parts herein described.

Figure 2 shows a bottom view of the fire box as shown in Figure 1.

Figure 3 is a detailed sectional view of the fuel ejector or mixer shown in Figure 1.

Figure 4 is a front elevation of the burner facing the fire door.

Figure 5 is a sectional view taken through the port holes of Figure 4.

Figure 6 is a sectional view taken on line 6—6 of Figure 1.

In the drawings 1 is the ejector body that holds the ejector tube 2. Tube 2 is held in casing 1 by a spanner nut 4. Nozzle 3 is held in casing 1 by the spanner nut 7. 4a is a pipe connection between the ejector body and burner head 5. 7 is a spanner nut which holds steel pipe 8 and nozzle 3 to body of ejector 1. 9 is a connection nut which holds fuel oil pipe 10 to body of ejector 1. 11 is a fuel oil valve which is connected by link 12 and through staff 13 to handle 14 which is manually operated. 15 is a steam tight casing around fuel pipe 10. Steam comes through pipe 16 into the upper end of casing or jacket 15 and surrounds fuel pipe 10, heating the oil and passes to the atmosphere through opening or vent 17.

The amount of steam admitted to jacket 15 is manually controlled by steam valve 18 which is fed from manifold 19 and which is in turn fed from main fountain valve 20 through pipe 21, placed in the dome, the highest part of the boiler, to obtain the driest steam possible. Valve 22 controls steam admitted to manifold 19. When valve 22 is open manifold 19 is continually charged with live steam. Pipe 8 leads from manifold 19 to ejector 1 and steam is controlled by a valve 23. Pipe 24 is a blow back pipe to clean out fuel oil line 10 in case of foreign matter getting into fuel line 10 and is controlled by valve 26.

Pipe 25 is a blow back pipe to clean out ejector 1 and burner head 5 and is controlled by valve 27. In pipe lines 24, 25, and 8 check valves 28 are placed to prevent fuel oil from flowing into these steam pipes when the engine is dead and no steam in pipes.

29 is the mud ring of the boiler which is drilled and tapped to receive the studs 30. To the bottom of mud ring 29 is secured a flat sheet of steel 31 which covers the entire bottom of the fire box and is made air tight between mud ring 29 and sheet 31 by asbestos padding or lagging and is held in place by the studs 30.

In the center of this sheet a stand 32 is placed

to support the connection 6 and the burner head 5. 33 is a casing around air inlet 34. Stand 32 and casing 33 are welded to sheet 31 and extend about six inches above the bottom of sheet 31. Common 5 rock ballast is placed on the sheet 31 over its entire surface up to the top of stand 32 and air inlet casing 33.

The amount of air admitted to the fire box 10 through inlet 34 for combustion is controlled by damper plate 35 which is raised or lowered manually by chain 36 which extends up through deck A of a cab (not shown) and held in any desired position by latching chain 36 in a steel plate which is slotted to receive links of chain and 15 fastened to deck or floor A.

As shown in Figures 4 and 5, holes 5a are drilled through the body of burner head 5 to allow the steam and fuel oil to spray over the back part of fire box. These holes 5a are drilled 20 from the bottom of burner head 5 starting in a horizontal row and then in two vertically inclined rows from the ends of the horizontal row to the top side of the burner head 5.

In operation as shown in Figure 1 steam is admitted 25 through valve 23 and pipe 8 which passes through nozzle 3. The expansion of the steam as it leaves nozzle 3 and enters tube 2 creates a vacuum in the body 1. This in turn has a tendency to draw the fuel oil from the fuel oil supply 30 pipe 10, the oil mixing with the steam as it leaves nozzle 3 and enters tube 2 and is forced up through the pipe 4a into the burner head 5 in the form of a spray or vapor where it is first ignited by a lighted piece of waste. The amount 35 of fuel oil supplied to the ejector and burner head 5 is manually controlled by the fireman through the handle 14, shaft 13, link 12, and fuel oil valve 11.

During the operation of the locomotive, when 40 it is necessary to build up a hotter fire, more oil is fed into the ejector body 1 by operation of the oil valve 11. It is usually desirable to mix more steam with the oil in the ejector body as the fire becomes hotter, so valve 23 is operated to increase 45 the use of steam. The oil feed valve 11 and steam valve 23 are shut off, when the locomotive demands less oil and steam. It is shown that the fire is thrown to the back head of the boiler and to the crown sheet 50, the air coming through 50 inlet 34 (which is caused by a blower or induced by the vacuum created by the exhaust steam of the locomotive in the front end or smoke box discharging through a restricted exhaust opening called a nozzle tip) lifts the fire upwards and 55 forward through the flues 50.

It is apparent that there is no need of any brick work on refractory lining along the fire box sheets as fire is spread to all parts of the fire box. Unlike the present recognized burner this mechanism 60 does not throw the fire to one certain point in a blow torch effect which would drive the water away from the fire box sheets and possibly burn same if the sheets were not protected by fire brick or other material.

As there is no brick work used in the arrangement herein described there is no need for the customary fire pan to support same and is therefore eliminated. Due to the fact that a much 65 softer fire is produced and that not as much draft 70

is needed to lift the fire a very much larger nozzle tip can be used in the front end which eliminates back pressure on the locomotive when it is working. This in turn makes a more efficient locomotive with less fuel consumption for the same amount of work than required by the same class locomotive with the present recognized burner and arrangement.

Other alterations and modifications in the form and arrangement of parts will readily suggest themselves to those skilled in the art and it is to be understood that such different forms of construction are contemplated as forming a part of this invention in so far as they fall within the scope of the appended claims.

What I claim as new is:

1. In a locomotive boiler the combination of a firebox having fire tubes extending therefrom, a burner positioned in the center of the bottom of the firebox, said burner having a series of openings in one side and in the top thereof, said openings being directed away from said fire tubes, and means for supplying a mixture of steam and oil to said burner.

2. In a locomotive boiler the combination of a firebox having fire tubes extending therefrom, a burner positioned in the center of the bottom of the firebox, said burner having a series of openings, said openings being in two spaced apart horizontal rows and having one of the rows longer than the other row, the said openings being directed away from the fire tubes, and means for supplying a mixture of steam and oil to said burner.

3. In a locomotive boiler the combination of a firebox having fire tubes extending therefrom, a burner positioned in the center of the bottom of the firebox, said burner having a series of openings in one side, the said openings being spaced in a horizontal row near the firebox bottom and two rows extending inclinedly upwardly and outwardly from the ends of the said horizontal row, the said openings being directed away from the fire tubes, and means for supplying a mixture of steam and oil to said burner.

4. In a locomotive boiler the combination of a firebox having fire tubes extending therefrom, a burner positioned in the center of the bottom of the firebox, said burner having a series of openings in one side, said openings being spaced in a horizontal row near the base of the burner and two rows extending inclinedly upwardly and outwardly from the ends of the said horizontal row and the upwardly and outwardly inclined rows converging with a second horizontal row near the top of the burner, said openings being directed away from said fire tubes, and means for supplying a mixture of steam and oil to said burner.

5. In a locomotive boiler the combination of a firebox having fire tubes extending therefrom, a burner positioned in the center near the bottom of the firebox, said burner having a series of openings in one side and in the top thereof, said openings being directed away from said fire tubes, and the firebox having an inlet in its bottom near the front thereof for supplying air to said burner to support combustion.
